UNITED STATES PATENT OFFICE

2,653,715

JIG

Walter C. Steinmetz, Columbus, Ohio, assignor
to The Jeffrey Manufacturing Company, a corporation of Ohio

Application June 6, 1950, Serial No. 166,395

6 Claims. (Cl. 209—457)

1

This invention relates to a jig and an object of the invention is to provide a jig in which high gravity material is discharged into the housing of an elevator which communicates with the material holding container portion of the jig, the communication between said container and housing being through a rotary valve, preferably a star wheel valve, to the end that the water pulsations in said container shall effectuate the separation of high gravity from low gravity material and will not produce surging of the water in the elevator housing.

Other objects of the invention will appear hereinafter, the novel features and combinations being set forth in the appended claims.

In the accompanying drawings:

Fig. 1 is a side elevational view, with the parts broken away and in section, showing a jig incorporating parts of my invention; and

Fig. 2 is a front end elevational view, with the parts broken away and in section, showing said jig.

Referring to the drawings, the illustrated embodiment of my invention includes a tank or container 10 having a pair of laterally spaced upright side walls between which there extends a perforated plate or screen 11 upon which a bed of material is adapted to be supported while undergoing stratification and gravity separation due to the cyclic upward and downward pulsations of the water through said screen 11 in an essentially standard and well known manner.

Intermediate the front and rear of the side walls of the container 10 there is a transverse generally upright partition 12, the upper portion of which is formed to provide a sloping feed chute 13 by which material to be separated is fed to the container 10 and supported by the screen 11. The screen 11 slopes gradually towards a high gravity discharge chute 14 formed above the discharge edge of feed screen 11 and below a low gravity discharge weir 15 over which low gravity material with a certain amount of water discharges in a standard manner.

A discharge of the high gravity material through the chute 14 is controlled by a star wheel type discharge valve having a float controlled ratchet operating mechanism 16, all of which is of generally standard construction and may follow, for example, the disclosure in Patent No. 2,132,378 dated October 11, 1938.

To the rear of the partition 12, and within the container 10, there is a pivoted piston or flapper 17 which is operated by a crank rod 18 from a power driven shaft 19 which shaft also

2

operates an eccentric rod 20 causing reciprocation of the pawl of discharge mechanism 16. The shaft 19 is driven from a motor 21 through appropriate belt or chain drive mechanism 22. Water is delivered at a controllable rate to the tank 10 through the feed pipe 23, provided with the usual control valve, not shown.

The bottom of the container 10, below the screen 11 and piston 17, provides a hutch compartment 24 the sides of which are sloped toward the center, as clearly illustrated in Fig. 1 of the drawings, thereby leading to a discharge chute 25 the bottom of which communicates with the bottom of a housing 26 of a bucket elevator 27 provided with endless draft chains 28, or the like, carrying spaced buckets 29 by which high gravity material delivered to the elevator 27, is elevated and discharged through a discharge chute 30. The draft chains 28 are driven from a motor 31 through a standard chain and sprocket or belt drive 32.

In jigs having the general construction above described as heretofore manufactured, there generally was direct and unrestricted communication between the container, similar to the container 10, and the elevator, similar to the elevator 27. This was obtained through the hutch compartment, similar to the hutch 24, or through a refuse discharge compartment which received the high gravity material through a chute, similar to the chute 14.

In such an arrangement two undesirable characteristics exist. First of all the pulsating up and down movement of the liquid through the screen 11 produces a similar pulsating up and down movement of the liquid in the elevator casing. In view of the fact that the material and water which went through the screen 11 was the only moving water which was producing a cleaning action on the bed of materials, this moving water alone was doing useful work. Furthermore, the resistance of this water to upward movement was obviously greater than that encountered by water substantially free to move upward through the elevator casing. As a consequence there was often appreciable greater cyclic movement of water upward and downward in the elevator casing, where it did no good, than through the screen 11 and the bed of materials thereon where it effectuated a separating action.

The second result, therefore, in such instances was the inefficiency of the unit, particularly in the inefficient use of the energy expended in producing the pulsating or cyclic up and down move-

ment of the water. These objectionable characteristics of such devices have been overcome and the pulsating movement of the water has been confined largely to useful movement through the screen 11 and the bed of materials thereon undergo stratification. To accomplish this, while at the same time providing for discharge of high gravity material from the screen 11 into the housing 26 of the elevator 27, it is to be noted that the high gravity material discharged through the chute 14 is delivered to the hutch compartment 24. Due to the slope of the adjacent bottom wall of said hutch compartment 24 this high gravity material will readily fall into the chute 25. Furthermore, any fines which are drawn by the suction stroke through the screen 11 will readily fall into the chute 25.

To control positively the movement of the high gravity material from the hutch compartment 24 into the chute 25, while isolating the hutch compartment 24 from the elevator housing 26, I provide a rotary star valve 33 adjacent the top of the chute 25 which is so constructed by the overlap of the plates of the rotor and adjacent opposite arcuate contacting valve walls as to prevent flow of water through the chute 25. The rotary valve 33 is preferably continuously rotated by appropriate drive mechanism 34, driven from the motor 21, so that high gravity material delivered to the entrance of the chute 25 will be fed by the rotor of feed valve 33 for delivery into the bottom of the housing 26. While some water will, of course, pass through the valve 33 said valve will prevent surging of the water upwardly and downwardly in said elevator housing 26, which would otherwise take place.

In the operation of the apparatus, materials of different specific gravity which are to be separated will be delivered to the feed chute 13 and into the container 10 above the screen 11 where a bed of materials will be formed. The motor 21 will be placed in operation and the desired amount of water continuously delivered to the tank 10. Piston 17 will be reciprocated with an arcuate movement producing the cyclic pulsion and suction strokes of the water through the screen 11 thus stratifying the bed of materials thereon. During each pulsion stroke a portion of the water and low gravity material will flow over the weir 15 and be discharged as a clean product or as refuse, as the case may be. The high gravity material will stratify in the lower portion of the material bed and the discharge rate thereof will be controlled by the float operated control mechanism 16. High gravity material thus discharged, together with any hutch material, will accumulate in the entrance of chute 25 and be fed from the hutch compartment 24 into the bottom of the elevator housing 26, through feed chute 25, and under the positive control of the rotary star valve 33, which is effective to confine the surges or pulsations of the water or fluid in the tank or container 10, and prevent such surges or pulsations in the housing 26 of elevator 27.

Obviously those skilled in the art may make various changes in the details and arrangement of parts without departing from the spirit and scope of the invention as defined by the claims hereto appended, and applicant therefore wishes not to be restricted to the precise construction herein disclosed.

Having thus described and shown an embodiment of the invention, what it is desired to secure by Letters Patent of the United States is:

1. A jig including a container adapted to hold water, a screen in said container upon which material is to be jigged, a weir adjacent said screen over which low gravity material flows with water, said container forming a hutch compartment below said screen, an elevator having a housing communicating with the hutch compartment of said container, means for causing a periodic upward flow of water through said screen, rotary high gravity discharge valve means adjacent said screen for discharging high gravity material to said hutch compartment, rotary star wheel valve means between said hutch compartment and said elevator housing effecting a seal therebetween through which high gravity material is discharged and operative for preventing surging of water in said elevator housing when it is caused to flow upwardly as aforesaid, and means to rotate said rotary star wheel valve means to discharge high gravity material from said hutch compartment into said elevator housing while preserving said seal therebetween.

2. A jig including a container adapted to hold water, a screen in said container upon which material is to be jigged, a weir adjacent said screen over which low gravity material flows with water, said container forming a hutch compartment below said screen, an elevator having a housing communicating with the hutch compartment of said container, means for causing a periodic upward flow of water through said screen, means adjacent said screen for discharging high gravity material to said hutch compartment, rotary star wheel valve means between said hutch compartment and said elevator housing effecting a seal therebetween through which high gravity material is discharged and operative for preventing surging of water in said elevator housing when it is caused to flow upwardly as aforesaid, and means to rotate said rotary star wheel valve means to discharge high gravity material from said hutch compartment into said elevator housing while preserving said seal therebetween.

3. A jig including a container adapted to hold water, a screen in said container upon which material is to be jigged, a weir adjacent said screen over which low gravity material flows with water, said container forming a hutch compartment below said screen, an elevator having a housing communicating with the hutch compartment of said container, means for causing a periodic upward flow of water through said screen, means adjacent said screen for discharging high gravity material, rotary star wheel valve means between said hutch compartment and said elevator housing effecting a seal therebetween through which high gravity material is discharged and operative for preventing surging of water in said elevator housing when it is caused to flow upwardly as aforesaid, and means to rotate said rotary star wheel valve means to discharge high gravity material from said hutch compartment into said elevator housing while preserving said seal therebetween.

4. A jig including a container adapted to hold water, a screen in said container upon which material is to be jigged, a weir adjacent said screen over which low gravity material flows with water, said container forming a hutch compartment below said screen, an elevator having a housing communicating with the hutch compartment of said container, means for causing a periodic upward flow of water through said screen, means adjacent said screen for discharging high gravity material, rotary valve means between said hutch

compartment and said elevator housing effecting a seal therebetween through which high gravity material is discharged and operative for preventing surging of water in said elevator housing when it is caused to flow upwardly as aforesaid, and means to rotate said rotary valve means to discharge high gravity material from said hutch compartment into said elevator housing while preserving said seal therebetween.

5. A jig including a cleaning container, means for causing a pulsation of water therein, an elevator having a housing communicating with said cleaning container, and rotary star valve means between said cleaner container and said elevator housing operable to deliver material therebetween while substantially preventing the surging of water between said cleaning container and said elevator housing and vice versa.

6. A jig including a cleaning container, means for causing a pulsation of water therein, an elevator having a housing communicating with said cleaning container, and rotary valve means between said cleaner container and said elevator housing operable to deliver material therebetween while simultaneously preventing the surging of water between said cleaning container and said elevator housing and vice versa.

WALTER C. STEINMETZ.
